EDWIN CHAPMAN, OF ROCHESTER, MINNESOTA.

Letters Patent No. 70,802, dated November 12, 1867.

IMPROVEMENT IN ROTARY ENGINES.

The Schedule referred to in these Letters Patent and making part of the same.

TO ALL WHOM IT MAY CONCERN:

Be it known that I, EDWIN CHAPMAN, of Rochester, in the county of Olmsted, and State of Minnesota, have invented a new and useful Improvement in Rotary Steam Engines; and I do hereby declare that the following is a full, clear, and exact description thereof, which will enable those skilled in the art to make and use the same, reference being had to the accompanying drawings, forming part of this specification.

This invention relates to certain useful improvements in the class of steam engines known as rotary engines, and it consists principally in the manner in which the abutments are operated, and in the manner in which the steam is discharged into the cylinder and exhausted therefrom.

Figure 1 is a vertical section of the engine, through the line *xx* of fig. 3.

Figure 2 is a vertical section of fig. 1, through the line *yy*.

Figure 3 is a top or plan view of the engine.

Figure 4 is a section through the line *zz* of fig. 1.

Similar letters of reference indicate corresponding parts.

This engine is attached to a frame, which sets on and is secured to a bed-plate. *A* represents the bed-plate. *B* is the frame, which is raised above the bed-plate, and rests on pillars *a*. *C* is the cylinder, which is formed of two parts or half cylinders, in which works the piston *D*. *E* is the engine shaft. *F* is the steam pipe, which is connected with the boiler. The steam enters the cylinder through the face of the piston at *c*, as seen in fig. 2. The piston is attached to a disk-plate, *d*, which is securely fastened to the shaft *E*, and is connected with the steam pipe *F* by a chamber which is made in the eye of the cylinder marked *e*. *f*, fig. 1, is an aperture from the cylinder to the centre of the shaft, which shaft is made hollow, as seen in fig. 2, for the exhaust of the steam. The chamber *e* is always under a pressure of steam, with an aperture, *g*, connecting it with the piston, so that whenever the piston passes the aperture *g*, the piston takes steam, or rather discharges steam through the aperture *e* against the abutments *h h*. The cylinder is slotted on each side, as seen in fig. 1, so that these abutments can play in and out. These abutments are attached to vertical shafts *i i*, which shafts are supported by wings *J J*, which project from each side of the cylinder. These wings are formed of two plates, each having recesses between them, into which the abutments are thrown when they are turned from the cylinder. The shafts *i* are packed by stuffing-boxes, *i'*, on each side of the wings, as seen in the drawing.

The manner in which these abutments are operated, so that they shall receive the full pressure of steam, and recede from the cylinder to allow the piston to pass at every revolution, is as follows: In the shaft at *k* there is an eccentric groove. *m m* and *m' m'* are arms, which are attached to vertical shafts *o o*. *n n* are brackets, by which the top ends of the shafts *o o* are supported. There are pins on the ends of the arms *m m'* which work in the eccentric groove *k*, so that as the shaft revolves the upright shafts *o o* are partially revolved or given a vibratory motion. To communicate this vibrating motion to the shafts *i i*, and thus operate the abutments *h h*, there are other arms on the shafts *o o* marked *m m'*. *p p* are rods, which connect the arms *m m'* with the shafts *i i* by short cranks or arms *o o*. The motion thus imparted to the abutments is sufficient to throw them entirely from the cylinder, as well as into it, at every revolution of the shaft *E*. Outside of the chamber there are small packing-rings, seen at *r*. These rings are tapering or wedge-shaped, and are cut like ordinary packing-rings in one or more places. As the surfaces wear, the spring of the ring, in its tapering seat, will force it out so that it will always insure a tight joint. Around the shaft *E* there are also packing-rings, *S S*, which are cut in one place, and spring into a recess, as seen in the drawing, for the purpose of insuring a tight joint between the shaft and the central portion or eye of the cylinder. The aperture *f* in the revolving disk-plate of the piston, being brought in communication with the hollow shaft twice in each revolution, the steam is exhausted thereby from the end of the shaft *E*.

Having thus described my invention, what I claim as new, and desire to secure by Letters Patent, is—

1. The arrangement of the steam-chamber *e*, aperture *g*, and packing *r*; with reference to the piston *D* and shaft *E*, as herein described, for the purpose specified.

2. The construction of the piston *D*, provided with the opening for discharging steam into the cylinder, and opening *f*, for exhausting the steam through the shaft, substantially as herein shown and described.

The above specification of my invention signed by me this 28th day of May, 1867.

EDWIN CHAPMAN.
